UNITED STATES PATENT OFFICE.

ANTON BECKER, OF COLUMBUS, OHIO, ASSIGNOR TO THE RALSTON STEEL CAR COMPANY, OF COLUMBUS, OHIO.

UNDERFRAME FOR CARS.

No. 863,580.

Specification of Letters Patent.

Patented Aug. 20, 1907.

Application filed May 10, 1907. Serial No. 372,940.

To all whom it may concern:

Be it known that I, ANTON BECKER, of Columbus, in the county of Franklin and State of Ohio, have invented certain new and useful Improvements in Under-frames for Cars; and I do hereby declare the following to be a full, clear, and exact description of the invention, such as will enable others skilled in the art to which it appertains to make and use the same.

My invention relates to improvements for under-frames for cars,—one object of the invention being to provide means whereby an underframe can be adapted to trucks of more than the usual height so that the coupling devices will be made to properly align with the coupling devices on cars having trucks of standard height.

A further object is to insure the proper alining of the outer ends of the bolsters and cross-bearers of an under-frame and insure the rigidity of the latter.

With these objects in view the invention consists in certain novel features of construction and combinations of parts as hereinafter set forth and pointed out in the claims.

In the accompanying drawings, Figure 1 is a trans-verse sectional view of a car, taken adjacent to one of the cross-bearers. Fig. 2 is a similar view adjacent to the bolster; and Fig. 3 is a longitudinal section of a portion of a car.

1 represents the center girder, comprising channels 2, 2. Cross-bearer members 3, 3, project outwardly from the respective channels of the center girder, each of said cross-bearer members consisting of channel iron and secured to the members of the center girder by means of angle-brackets 4. A tension plate 5 is disposed upon the members of the cross-bearer, extends across the top of the center girder and is bolted to the upper flanges of said cross-bearer members. Diaphragms 6 are secured at their upper edges to the cross-bearer members and are provided at their inner ends with flanges 7 lying against the outer faces of the center girder members. A filler 8 is disposed between the center girder members and provided at its ends with flanges 9. Bolts 10 pass through the flanges 7 of the diaphragms, through the center girder members and through the flanges 9 of the filler 8. Flanges 11 project laterally from the inclined lower edges of the dia-phragms 6 and to these flanges a compression plate 12 is secured, the intermediate portion of said plate extending across the bottom of the center girder.

Each bolster of the underframe comprises two pairs of channel members 13 secured at their inner ends to the sides of the center girder by means of angle-brackets 14. A tension or cover plate 15 is mounted upon the bolster, secured to the flanges of the members there-of and extends across the top of the center girder, as shown in Fig. 2.

In order to adapt the underframe to trucks of more than usual height, the members of the center girder are recessed, as shown at 16, and between the center girder members, above the recessed portion 16, a casting 17 is secured and made with a socket 18 for the reception 60 of the upper end of the pin which connects the under-frame with the truck.

Angle-bars 19 are secured to the outer faces of the center girder members immediately over the recessed portions of the latter. Diaphragms 20 are secured at 65 their upper edges to the bolster members and at their inner ends are provided with flanges 21 securely riveted to the angle-bars 19. The intermediate portion of a compression plate 22 (preferably heavier or thicker than the compression plate 12 secured to the cross- 70 bearer diaphragm), has its intermediate portion passing through the recesses 16 of the center girder members and bearing against the outwardly projecting members of the angle-bars 19. This compression plate 22 ex-tends in both directions from the center girder to points 75 in proximity to the outer ends of the diaphragms 20 and are bolted to the flanges 23, projecting laterally from the inclined edges of said diaphragms. A bottom plate 24, adapted for co-operation with a truck, is lo-cated within the recessed portion 16 of the center, 80 girder and provided with flanges 25. Bolts 26 pass through these flanges, the compression plate 22 and the angle-bars 19 for securing the bottom plate 24 in place.

By means of the construction above described I am enabled to mount the underframe upon trucks of more 85 than standard height and to compensate for the difference in height between such trucks and those com-monly employed, to insure proper alinement of the coupling devices between cars.

Angle-iron members 27 located at respective sides of 90 the underframe, extend from one end to the other of the car underframe and are secured to the outer ends of the cross-bearer members and the bolster members by means of angle-brackets or gussets 28. The upper horizontal portions of the angle-iron bars or members 95 project over the ends of the cross-bearers and bolsters and have the side stringers 29 secured upon them.

Intermediate stringers 30 are mounted upon and secured to the cross-bearers and bolsters by means of bolts which also secure the flooring 31 upon the string- 100 ers. Angle-iron bars or members 32 connect the angle-members or bars 27 at the ends of the underframe; are located behind the end sills 33 and are secured to the center girder by means of angle-brackets 34,—said angle-members or bars 32 thus constituting abut- 105 ments for the end sills, and the angle-members 27, at the sides of the underframe, insuring the proper alinement of the cross-bearers and bolsters and the rigidity of said underframe.

Various slight changes might be made in the details 110.

of my invention without departing from the spirit thereof or limiting its scope and hence I do not wish to restrict myself to the precise details herein set forth.

Having fully described my invention what I claim 5 as new and desire to secure by Letters-Patent, is,—

1. A car underframe comprising a center girder, cross-bearers and bolsters secured to the center girder, angle-bars secured to the ends of the cross-bearers and bolsters and extending from end to end of the underframe, and 10 angle-bars at the ends of said underframe and extending from one of said first mentioned angle-bars to the other, said end angle bars constituting abutments for the end sills of the car.

2. A car underframe comprising a center girder, cross-bearers and bolsters secured thereto, end sills, angle-bars 15 at the ends of the underframe behind the end sills, and means securing said angle-bars to the center girder.

3. In a car underframe, the combination of a center girder, bolster members secured thereto, said center girder having a recessed portion below the bolster, diaphragms 20 secured to the bolster members, and a compression plate extending through the recessed portion of the center girder and secured to said diaphragms.

4. In a car underframe, the combination of a center girder, bolster members secured thereto, said center girder recessed below the bolster, reinforcing angle-bars secured to the center girder over the recessed portion thereof, diaphragms secured to the bolster members and to said reinforcing angle-bars, and a compression plate disposed under said angle-bars, passing through the recessed portion of 30 the center girder and secured to the bolster diaphragms.

5. In a car underframe, the combination of a center girder, bolster members secured thereto, said center girder recessed below the bolster, angle-bars secured to the center girder over the recessed portion thereof, a compression plate passing through the recessed portion of the center girder, bolster diaphragms secured to the bolster members and to said compression plate, and a bottom plate for co-operation with a truck, secured to said compression plate. 35

In testimony whereof, I have signed this specification 40 in the presence of two subscribing witnesses.

ANTON BECKER.
